FRANK M. DALE, OF SULLIVAN, INDIANA.

DRILLING APPLIANCE.

1,301,395.

Specification of Letters Patent. Patented Apr. 22, 1919.

Application filed June 21, 1918. Serial No. 241,116.

To all whom it may concern:

Be it known that I, FRANK M. DALE, a citizen of the United States, residing at Sullivan, Sullivan county, and State of Indiana, 5 have invented and discovered certain new and useful Improvements in Drilling Appliances, of which the following is a specification.

My invention relates to well drilling appliances and the objects of the invention are to provide means to render practicable for oil well boring, appliances of that type in which rotary cutting means are adapted to form successive cores of earth in their drilling descent; to increase the facility and rapidity of the removal of the successively excavated masses of earth in machines of this type whether the same be employed for oil well drilling or for other boring purposes, 15 and particularly in accomplishing the above general ends; to provide means whereby only the cutting tool and its operating mechanism are required to be operated in separating the successively formed cores from the 20 earth and merely the removal of such tool and its mechanism from the hole required to permit the removal of the material without necessitating the withdrawal of the surrounding casing; and to generally improve 25 the construction of drilling appliances. 30

With these objects in view, my invention is embodied in preferable form in the construction and arrangement hereinafter described and illustrated in the accompanying 35 drawings.

In these drawings, Figure 1 is a vertical section of a well drilling casing and drilling appliance; Fig. 2, a bottom section on the line 2—2 of Fig. 1, showing the core cutters 40 constituting the principal feature of my invention; Fig. 3, a section on the same line showing the core cutters forced into their core cutting position; Fig. 4, a bottom plan looking up, of the cutting core bit; Fig. 5, a 45 detail of the lower end of the core shell and Fig. 6, a detail perspective of a modified form of the core cutters.

Referring to the drawings, 1 indicates a well casing adapted to be driven into the 50 well as the hole is bored. 2 indicates a raising and lowering cable for the well drilling mechanism, which cable may be secured to the end of a squared connecting bar 3 fixed 55 in the head 4 of the sliding guiding shell 5 provided with guides 6. This bar is connected to the supporting rod or fixed shaft

7 of an electric motor 8. The revolving armature shaft 9 of this motor extends from the lower end thereof and on this shaft are fixed under cutters 10 adapted to enlarge 60 the hole formed by the boring bit so as to permit the casing to more readily descend. Fixed to the armature shaft so as to rotate therewith is a hollow, cylindrical shell 11, 65 constituting the rotary core bit. This core bit is provided in its lower circumferential edge with cutters 12 adapted to cut into the soil and form a cylindrical hole. Mounted on pivot pins 13 fixed in slots 14 formed in the shell of the core bit 11 are swinging cutter 70 members 15 having cutting points 16 at their ends. These cutter members are adapted to lie on the surface of the wall of the core bit within the slots when closed in inoperative 75 position as shown in Fig. 2, and they are 75 adapted to be swung inward toward the center of the core bit by means of pins 17 projecting downwardly from a hollow shell or frame 18 mounted within the cylindrical 80 core bit. This inward movement of the cutters 85 by their contact against the pins 17 is effected by producing a relative rotative movement between the frame or shell 18 and the surrounding core bit whereby the cutters travel 90 against the pins and are thus caused to swing 85 on their pivots. The frame or shell 18 is provided with depending shoulders 19, one 90 opposite each swinging cutter member and adapted to project downward against the inner edge of the latter to normally retain the same in closed or inoperative position upon 95 the slot wall of the core bit and adapted to be released from such retaining engagement by an upward movement of the shell or frame 18. At its upper end the shell 18 is 100 provided with a head or disk 20 having a squared, central opening adapted to engage a squared head 21 at the lower end of the rotary driving shaft 9. A spring 22 bears 105 against the disk 20 and serves to normally maintain the frame in its downward position and with the squared portion thereof in engagement with the head 21. Above said head 21 is a reduced circular portion 23 to 110 which the squared aperture of the disk 20 is adapted to be lifted to permit of the release of the frame or shell 18 from engagement with the rotary shaft so as to enable the said frame and the shaft and core bit to be rotated relatively. To enable this relative movement to be obtained a coiled spring 24 110 is secured at one end of a boss rising from

- the disk 20 of the interior shell 18 and at the other end to the core bit. This spring is adapted to be wound up so as to impose a tension upon the same before the squared 5 aperture in the head 20 is engaged with the squared head 21 on the shaft and is wound in such a direction that it will tend to unwind in a direction opposite to that of the rotation of the core bit, so that when the shell 10 is released from fixed engagement with the shaft the spring 24 will impose a tension upon the shell tending to turn it oppositely to the movement of the core bit so that a relative rotative movement will be produced 15 between said parts by means of which the cutters will be carried against the pins 17 and thus forced inwardly toward the center. The operation of the device is as follows:—
- 20 The hole is drilled by the rotation of the shaft 9 through the electric motor 8 and as such drilling proceeds the drilling mechanism is gradually lowered by means of the cable 2 and at a desired depth, the casing 25 3 is inserted into the hole thus formed, the pivoted under cutters 10 preferably preceding the casing and cutting the hole wide enough for the free insertion of the latter. As the core bit descends the material cut 30 from the earth will be forced up within the same in the form of a core. When the upper end of this core which may, of course, be composed either of loose earth, sand, mud or water or solid rock, bears against the head 35 20 of the shell 18 it will lift said shell thus releasing the shoulders 19 from engagement with the inner edges of the core cutters 15 and in the farther upward movement of the shell the latter will slip off the squared head 40 21 of the shaft, thus releasing the shell from engagement with the shaft, whereupon the wound spring 24 will tend to twist the shell in the opposite direction of rotation to that of the core bit. The rotation of the core 45 bit is continued but the latter is prevented from further descent by holding taut the cable 2, whereupon the core cutters 15 in the rotary movement of the bit relative to the shell 18 will ride against the pins 17 forcing 50 the cutters inwardly so that they will cut through the core. After the core has been cut the drilling mechanism is raised by means of the cable 2 up through the casing, carrying with it, on the cutters 15, such 55 part of the core as may be capable of being supported thereby and then the remainder of the core is removed by a suitable bail as is customary. By this method it will be seen that the core may be removed for inspection of the material excavated at different depths or to enable the well to be cleared without the removal of the casing or without operating the same to effect the separation of the core from the earth below 60 it. In the upward movement of the drilling 65

mechanism the under cutters 10 are adapted to swing down as the same are drawn up through the casing.

In Fig. 5, there is shown a modification of means for rocking the cutters on their pivots 70 consisting of cutters 25 mounted on the lower ends of shafts 26 adapted to extend up through the wall of the floor bed and to the upper ends of which shafts are fixed plates 27 carrying pins 28 adapted to engage in 75 cam slots 29 formed in the upper head of the core operated shell, which may be of similar construction to that shown in Fig. 1.

It is clear that various means of operating the core cutting members may be employed without departing from the principle 80 of my invention.

Having thus described my invention, what I claim is:—

1. A drilling appliance having a rotative 85 hollow core bit having boring cutters, core severing means, means for controlling the operation of said severing means and normally rotatable with the bit and automatically operable by the contact of the core 90 therewith to establish a relative rotative relation between the same and the bit, and including means for effecting the operation of said severing means by said relative rotation of the parts. 95

2. A well drilling appliance having a rotative hollow core bit, pivoted horizontally swinging core cutters, a member normally rotatable and vertically movable with the core bit and adapted for limited vertical 100 movement relative thereto by contact of the core therewith to release said member from rotation effecting engagement with the bit, means for detaining said member to establish a relative rotation between the same 105 and the core bit and means carried by one of said parts for forcing the cutters inwardly upon such relative movement to effect the cutting of the core.

3. A drilling appliance having a rotative 110 hollow core bit, swinging core cutters mounted upon said core bit, a hollow member having a limited vertically sliding movement and mounted within said core bit and having means for normally fixing it to the 115 bit for rotation therewith and releasable from such fixed engagement by contact of the core therewith, a spring for holding said member against rotation with the core bit and contact means carried by the said member 120 for operating said cutters in the relative rotative movement of the core bit and said member.

4. A drilling appliance having a rotative hollow core bit, horizontally swinging cutters mounted on said core bit, a hollow vertically slid able member mounted within said core bit and having means of fixed engagement with the rotating bit, a spring for holding said member in such engagement, 125 130

means to release said member from said engagement by contact of the core therewith, a spring under tension and acting to tend to turn said member in the opposite direction to that of the rotation of the core bit, contact means carried by said member adapted to bear against the cutters to swing them inwardly to cut the core and means carried by said member for normally retaining the 10 cutters in inoperative position and for re-

leasing them from such engagement when the member is operated by the core.

In witness whereof, I have hereunto set my hand and seal at Indianapolis, this 17th day of June, A. D. nineteen hundred 15 and eighteen.

FRANK M. DALE. [L.S.]
